UNITED STATES PATENT OFFICE.

WILLIAM M. BATES, OF SCOTTSBORO, ALABAMA.

DESIGN FOR A CHURN-STAND.

Specification for Design.

Patented July 15, 1913.

• 44,331.

Application filed April 28, 1913. Serial No. 764,283. Term of patent 3½ years.

To all whom it may concern:

Be it known that I, WILLIAM M. BATES, a citizen of the United States, residing at Scottsboro, in the county of Jackson and State of Alabama, have invented a new, original, and ornamental Design for Churn-Stands, of which the following is a specification, reference being had to the accompanying drawings, forming a part thereof.

The figure is a perspective view of the churn stand.

I claim:

The ornamental design for a churn stand, as shown.

WILLIAM M. BATES.

Witnesses:

ALEXANDRIA BEECH,
J. C. BATES.
